Primary Examiner — Mark Goodwin(74) *Attorney, Agent, or Firm* — Brian D. Bellamy(57) **CLAIM**

The ornamental design for a wall stud insert shield, as shown and described.

DESCRIPTION

FIG. 1 is a side, front and top perspective view of a wall stud insert shield, showing an embodiment of my new design; FIG. 2 is a front elevation view thereof, whereas the rear is an identical mirror image; FIG. 3 is a right side elevation view thereof, whereas the left side is an identical mirror image; FIG. 4 is a top elevation view thereof; and, FIG. 5 is a bottom elevation view thereof. The figures are shown broken apart to represent indeterminate length.
